UNITED STATES PATENT OFFICE.

JOSEPH A. WILLIAMS, OF CAMBRIDGE, MASSACHUSETTS.

DESIGN FOR A BADGE.

SPECIFICATION forming part of Design No. 25,305, dated March 31, 1896.

Application filed February 12, 1896. Serial No. 579,087. Term of patent 7 years.

To all whom it may concern:

Be it known that I, JOSEPH A. WILLIAMS, a citizen of the United States, residing at Cambridge, in the county of Middlesex, State of Massachusetts, have invented a new and original Design for a Badge, of which the following is a specification, reference being had to the accompanying drawing, forming part thereof.

The drawing shows the face of a badge illustrating my design.

The leading feature of my design consists in the representation of a mariner's compass-card upon a circular base, in the center of which base is displayed a Maltese cross, four of the quartering points of the compass-card being extended between the arms of the cross, and a shield upright is represented centrally on and covering the bases of the arms of the Maltese cross. As shown in the drawing, the Maltese cross is of conventional shape, and

the central portion thereof is covered by an upright shield, the whole being displayed upon a circular base bearing the representation of a mariner's compass-card, also of conventional form. The cardinal points of the compass-card are herein shown as extended inwardly between the arms of the cross, which latter thus has the appearance of being arranged diagonally upon the said compass-card.

The design is shown as embodied in a badge.

What I claim is—

The design for a badge, substantially as shown and described.

In testimony whereof I have signed my name to this specification in the presence of two subscribing witnesses.

JOSEPH A. WILLIAMS.

Witnesses:

JOHN C. EDWARDS,
AUGUSTA E. DEAN.
